(57) **CLAIM**

The ornamental design for a flippable electronic device as shown and described.

DESCRIPTION

FIG. 1 is a perspective view of a flippable electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the indicated portion of the flippable electronic device labeled "8" in FIG. 1;

FIG. 9 is an enlarged view of the indicated portion of the flippable electronic device labeled "9" in FIG. 1;

FIG. 10 is a perspective view thereof in another position; and,

FIG. 11 is a perspective view thereof in another position where the screen is flipped obliquely.

The even-dash broken lines illustrate portions of the flippable electronic device that form no part of the claimed design. The dot-dash broken line represents a bounded area within the claimed design. This claimed area extends to the boundary line but does not include the boundary line. The dot-dot-dash broken line rectangles in FIG. 1 indicate the extents of the enlarged views and form no part of the claimed design.
